UNITED STATES PATENT OFFICE

161,608

CHILD'S BIB

James R. Arseneault, Worcester, Mass., assignor to Olive L. Buell, Worcester, Mass.

Application April 10, 1950, Serial No. 9,116

Term of patent 14 years

(Cl. D3—26)

To all whom it may concern:

Be it known that I, James R. Arseneault, a citizen of the United States, residing at Worcester, county of Worcester, and State of Massachusetts, have invented a new, original, and ornamental Design for Child's Bib, of which the following is a specification, reference being had to the accompanying drawing, forming part thereof.

Fig. 1 is a view in front elevation of a child's bib;

Fig. 2 is a central vertical section thereof;

Fig. 3 is a view in side elevation thereof; and

Fig. 4 is a section on line 4—4 of Fig. 3, showing my new design.

I claim:

The ornamental design for a child's bib, as shown.

JAMES R. ARSENEAULT.
